UNITED STATES PATENT OFFICE.

HARRY J. LEBHERZ, OF FREDERICK, MARYLAND, ASSIGNEE TO THE EVERYREDY COMPANY, OF FREDERICK, MARYLAND, A CORPORATION OF MARYLAND.

BOTTLE-CAPPING TOOL.

Application filed November 18, 1925. Serial No. 69,868.

My invention relates broadly to bottle capping tools and more particularly to a construction of bottle capping heads and lever operating means for applying such heads upon bottles in the process of capping such bottles.

One of the objects of my invention is to provide a bottle capping tool in which spring means are provided for normally maintaining the capping lever out of engagement with a vertically extending rack upon which the capping head of a bottle capping tool is arranged to be operated.

Another object of my invention is to provide an attachment which may be readily applied to a pivotal mounting of a bottle capping tool by which the hand lever which is utilized for operating the capping head of a bottle capping tool may be returned to an initial operating position after each application of the capping head against a bottle which is to be capped by the use of such tool.

Still another object of my invention is to provide a simplified attachment for the pivotal axis of the hand lever in a bottle capping tool by which spring tension may be maintained on the hand lever for normally raising the bottle capping head which is secured to said lever out of engagement with the bottle in the process of capping, enabling the capping head to be readily applied to bottles to be capped in successive operations.

My invention will be more clearly understood from the following specification, by reference to the accompanying drawings, wherein:

Figure 1 is a side elevation of the bottle capping tool of my invention equipped with a capping head and the spring attachment for the hand lever thereof constructed in accordance with my invention; Fig. 2 is a fragmentary view taken through one side of the bottle capping head and showing the hand lever in its lowermost position in the process of applying a cap upon a bottle; Fig. 3 is a fragmentary view of the bottle capping head showing the capping lever raised in its uppermost position in such manner that the bottle capping head may be moved to any desired point along the vertically extending rack; Fig. 4 illustrates the bottle capping head with the hand lever in position where a cap is about to be placed

upon a bottle; Fig. 5 is a view partially in cross-section taken on line 5—5 of Fig. 1 through the bottle capping head and illustrating the spring means which I provide and attachment which is secured upon the 60 pivot point of the bottle capping head for engagement with the hand lever thereof; Fig. 6 is a plan view of the bottle capping head showing the relation of the attachment which is positioned on the bottle capping 65 head at the fulcrum thereof with the spring means for urging said attachment against the end of said hand lever at all times; Fig. 7 is a perspective view of one form of trigger used in the assembly of the bottle 70 capping tool; and Figs. 8, to 12 show a modified construction of trigger and side plates for the bottle capping head on the bottle capping tool. The details of construction of the bottle capping tool of my 75 invention are described more particularly in Letters Patent Nos. 1,356,161, dated October 19, 1920, granted to Harry J. Lebherz, Reissue 15,285, dated February 14, 1922, granted to Harry J. Lebherz, and 1,421,698, dated July 4, 1922 and granted to Harry J. Lebherz.

In the present invention I have illustrated an attachment for the bottle capping tool set forth more particularly in the aforementioned Letters Patent, by which the hand lever of the bottle capping tool is normally maintained in operating position at all times and returned to an initial operating position after each successive capping 80 operation. I provide an inexpensive flat circular plate member having one side extended out of round, with a pair of lugs extended therefrom and bent at right angles to said flat circular plate and in opposite 85 directions to said plate. The flat plate is secured upon the pivotal axis of the hand lever and one of the outstanding lugs on said plate engages the extremity of the hand lever, while the other of said lugs is engaged by spring means which normally tends to 90 secure the opposite lug into abutment with the lower end of the hand lever. The lug which abuts with the lower end of the hand lever is constantly urged against the hand lever in such manner that there is a tendency for the hand lever to move to its uppermost position after each application of the 95 bottle capping tool in the process of capping a bottle. The lug which engages the end 100

105

110

portion of the hand lever also serves as a spacing member to maintain the hand lever out of gear with the vertical rack portion when the lever is thrown to a vertical position for changing the height above the base of the capping tool at which the capping head is operated.

Referring to the drawings in more detail, reference character 1 designates the base of the bottle capping tool on which is erected the vertical standard 2 carrying a rack 3 at its upper extremity. The standard 2 is provided with laterally extending guide rails 4 which serve to permit the free vertical movement of the capping head 5. The capping head 5 carries the capper throat 6 which is applied in the direction of the bottles which are to be capped for successive capping operations. A hand lever 7 is pivoted at 8 in the upper extremity of the bottle capping head 5 and carries at its lower extremity a set of teeth 9 which mesh with the teeth formed in the rack 3 for operating the bottle capping head in a vertical direction along the rack 3 in the process of successively applying caps to bottles. The attachment of my invention is shown more clearly in Fig. 7 as comprising a flat plate member 10 having a central aperture 10a therein which fits over the pivotal mounting 8 on which the lever 7 is fulcrumed. The flat plate 10 is substantially circular with an elongated portion 11 at one side thereof from which lug portions 12 and 14 extend on opposite sides of the plate 10. The lug portion 12 is bent at right angles with respect to the plate 10 and extends to a point between the side plates 5a and 5b which comprise the bottle capping head, and then is again turned at right angles forming the downwardly directed hook end 15 which abuts with the surface 16 at the lower extremity of the hand lever 7. The lug 14 extends at right angles to the plate 10 in a direction opposite to the direction of the lug 12, that is outwardly in a direction from the bottle capping head 5. The lug 14 is apertured at 14a and a spiral spring 17 is hooked between the aperture 14a and a point 18 on the bottle capping head 5. I have shown the side plate 5a as notched with the hook portion 17a of the spiral spring 17 secured therein, but it will be understood that an outstruck portion may be provided on the bottle capping head 5 and the end of the spiral spring secured therein.

In Figures 8, 9, 10 and 11 I have shown the side plates 5a and 5b as provided with notches 20 and 21 against which the lateral portion 12 of the trigger 10 abuts. The lever is thrown into upper position as represented in Fig. 9 thereby eliminating the tendency of the trigger to be bent when the handle is thrown upwardly into changing position.

60 The side plates 5a and 5b are so notched at

20 and 21 that the trigger portion 12 drops into the notches 20 and 21 and limits the movement of the lever 7 in the direction of the rack 3. Various shapes may be given to the side plates 5a and 5b to control the movement of the hand lever under action of the trigger. The shape of the trigger to cooperate with the notched side plates 5a and 5b is varied from the shape shown in Fig. 7 as represented in Fig. 12 omitting the hook 75 shaped portion 15 therefrom.

In the operation of the bottle capping tool the hand lever 7 is thrown up in a vertical position as represented in Fig. 3 in order that the bottle capping head 5 may be adjusted to any desired position for capping various types of bottles. In this position the lug 12 with hook end portion 15 will serve as a stop to maintain the teeth 9 on the extreme end of the hand lever 7 out of mesh with the teeth of the rack 3. In the process of capping a bottle the hand lever 7 is moved downwardly as represented in Fig. 4 and when a position is reached where the capper throat 6 engages a bottle the lower extremity 16 of the hand lever 7 abuts with the lower extremity of hook portion 15 and the capper throat 6 is moved downwardly against the action of spring device 17 to an extreme position illustrated in Fig. 2 when the bottle capping operation is complete. The depending or hook portion 15 enables the hand lever 7 to be moved downwardly to an extreme lowermost position as represented in Fig. 2. The spring 17 tends to constantly urge the hand lever into a normal operating position and after each successive capping operation the member 10 is drawn by virtue of spring pressure exerted by coil spring 17 to a position where the lug portion 12 abuts against the top of the side plate 5a of the capping head 5, raising the hand lever to a position where it is ready for the next capping operation.

It will be observed that the plate member 10 may be readily manufactured inexpensively on a quantity production basis. While I have shown my invention in certain preferred embodiments, I desire that it be understood that modifications may be made and that I intend no limitations upon the invention other than those imposed by the scope of the appended claims.

What I claim and desire to secure by Letters Patent of the United States is as follows:

1. In a bottle capping tool, the combination of a vertical rack member, a capping head adjustably arranged on said rack member, a capper throat carried by said capping head, a hand lever pivotally mounted in said capping head and having teeth at the end thereof for engagement with said vertical rack member, a flat plate member journaled on the pivot of said hand lever, and

being substantially circular in shape with lug members extending laterally from said plate member at an angle with respect to each other, one of said lugs extending over said capping head and having a hook shaped end thereon arranged to abut with the lower extremity of said hand lever, resilient means positioned between a point on said capping head and the other of said lug members for constantly urging said hook shaped lug member into engagement with said hand lever.

2. In a bottle capping tool, the combination of a vertical rack member, a capping head adjustably arranged on said rack member, a capper throat carried by said capping head, a hand lever pivotally mounted in said capping head and having teeth at the end thereof for engagement with said vertical rack member, a flat plate member journaled on the pivot of said hand lever, said plate member having a pair of lugs extending laterally therefrom, one of said lugs being bent upon itself and arranged to engage the lower extremity of said hand lever and the other of said lugs being resiliently connected with a point on said capping head whereby said hand lever is constantly urged in raised position.

3. In a bottle capping tool, the combination of a vertically extending rack member, a capping head adjustably arranged on said rack member, a capper throat carried by said capping head, a hand lever pivotally mounted in said capping head, a flat plate member concentrically mounted on the pivot of said hand lever and having a pair of lug

extensions thereon, one of said lug extensions forming a spacing member between one side of said hand lever and said rack member, and the other of said lugs being resiliently connected with a point on said capping head, said first mentioned lug forming an abutment with said hand lever and tending to return said hand lever to normally raised position after each successive operation of said capping tool.

4. In a bottle capping tool the combination of a vertically extending rack member, a capping head slidably mounted on said rack member comprising a pair of plate members located on opposite sides of said rack member, said plate members forming a journal in the upper extremity thereof for a hand lever having teeth thereon arranged to engage with said rack member, a flat plate member positioned on said journal and having a pair of lug members extending at right angles therefrom with one of said lug members being formed in the shape of a hook with its lower extremity depending between said plate members and forming an abutment for the lower end of said hand lever, and the other of said lug members being resiliently connected with a point on said capping head whereby downward movement of said hand lever tends to increase the tension exerted on the lower end thereof by said hook shaped member, whereby said hand lever is successively returned to normal position after each operation of said bottle capping head.

HARRY J. LEBHERZ.

CERTIFICATE OF CORRECTION.

Patent No. 1,681,144.

Granted August 14, 1928, to

HARRY J. LEBHERZ.

It is hereby certified that the name of the assignee in the heading to the printed specification of the above numbered patent, was erroneously printed as "The Everyredy Company", whereas said name should have been printed as "The Everedy Company", as shown by the records of assignments in this office; and that the said Letters Patent should be read with this correction therein that the same may conform to the record of the case in the Patent Office.

Signed and sealed this 28th day of August, A. D. 1928.
